UNITED STATES PATENT OFFICE.

LESTER SLATER MACDONALD, OF BEVERLY, MASSACHUSETTS.

LACING-HOOK.

1,117,413.

Specification of Letters Patent. Patented Nov. 17, 1914.

Application filed September 11, 1913. Serial No. 789,239.

To all whom it may concern:

Be it known that I, LESTER SLATER MACDONALD, a citizen of the United States, residing in Beverly, in the county of Essex and State of Massachusetts, have invented 5 an Improvement in Lacing-Hooks, of which the following description, in connection with the accompanying drawings, is a specification, like characters on the drawings representing like parts.

This invention relates to a lacing hook especially designed and adapted for use on ladies' boots and shoes to prevent the clothing from catching in the hook and being 10 torn thereby.

The present invention has for its object 15 to provide a lacing hook of the character described, which possesses the function described, and which is constructed as will be 20 described to render it commercially available for the purpose specified. To this end, the lacing hook is made from a single piece 25 of sheet metal and comprises a barrel member and a hook member, the barrel member being provided with a head to cover and 30 substantially close it at one end and from which the hook member extends laterally, the said hook member having a turned- 35 under finger, which is designed to make contact with or be brought in close proximity to the shoe upper so as to prevent the entrance into the hook of the clothing of the wearer of the shoe.

The hook member is preferably provided 35 with curved side edges and with vertical and horizontal concavities, as will be described, to impart strength to the hook member and also to avoid sharp edges which would chafe or cut the lacing.

40 These and other features of this invention will be pointed out in the claims at the end of this specification.

Figure 1 is a side elevation of a lacing hook embodying this invention. Fig. 2, a 45 plan of the sheet metal blank from which the lacing hook shown in Fig. 1 is made. Figs. 3, 4 and 5, details to illustrate the different formations through which passes the blank shown in Fig. 2. Fig. 6, a section on the line 6—6, Fig. 3. Fig. 7, a section on the line 7—7, Fig. 4. Fig. 8, a section on the line 8—8, Fig. 5.

55 Referring to the drawing *a* represents the barrel member of the improved lacing hook; *b* the head which closes the upper end of the barrel; *c* the hook member, which

comprises an arm 10 extended from the head *b* at an angle thereto; a substantially vertical finger 12 extended substantially at right angles from the end of the arm 10 and 60 a substantially horizontal finger 13 extended from the finger 12 toward the barrel *a* and substantially parallel with the arm 10.

The lacing hook shown in Fig. 1 is made 65 from the sheet metal blank 14, shown in Fig. 2, by means of suitable dies, not shown, and in Figs. 3, 4 and 5, are illustrated the different steps through which the blank 14 passes in order to produce the lacing hook shown in Fig. 1. These steps may be briefly 70 described as follows: The blank 14 is first pressed up into the form shown in Fig. 3, to form at the rear end the curved, upright flange 16 and at the front end the upright flange 17 and the intermediate portion or 75 arm 10, which is curved downwardly from the head *b*. On the next operation or step, the free ends of the curved flange 16 are brought together or in close proximity to each other to form the cylinder or barrel *a*, 80 and the head *b*, which covers one end thereof, the said barrel being of smaller diameter than the said head, so that an annular shoulder 20 is formed, which is designed to rest on the leather or other material through 85 which the barrel *a* is inserted. At the same time the barrel *a* is formed, the sides of the arm or intermediate portion 10 of the blank are turned downwardly and the upright flange 17 is bent outwardly at its upper end 90 and concaved transversely. In the next operation, the upper end of the flange 17 is bent into a position substantially parallel with the arm 10 to form the horizontal finger 13 and the vertical finger 12, which 95 latter is concaved transversely, and at the same time the sides of the intermediate portion or arm 10 are still further curved outwardly and downwardly, so as to provide smooth or rounded edges.

100 The finger 13 occupies a position substantially in the plane of the shoulder 20, so that it will contact with the leather or other material or be brought in close proximity thereto, to form a closure for the hook and 105 thus prevent the entrance of the trimmings or other part of ladies' skirts or dresses from being caught by the hook.

From the above description, it will be seen that the barrel is closed at its top by 110 a head from which projects laterally the arm 10 of the hook, which arm is preferably

curved transversely, and that the finger 13 and the vertical finger 12 are both concaved so as to strengthen them, whereby the hook member is made strong and durable so as to render it commercially available. The 5 lacing hook above described, may be finished in any suitable or well-known manner. Furthermore, it will be observed that the lacing hook is free from sharp or cutting edges, so that the lacing can be drawn 10 through the hook without danger of being cut or chafed.

Claims:

1. A one-piece sheet metal lacing hook 15 of the character described, comprising a barrel member provided at one end with a head integral with it and substantially closing the barrel at that end, and a hook member extended from and integral with said head and comprising an arm extended laterally away from said head, a flange extended from said arm substantially at right angles thereto, and a finger extended from said flange substantially at right angles thereto 20 and toward said barrel substantially parallel with said arm, substantially as described.

2. A one-piece sheet metal lacing hook 25 of the character described, comprising a barrel member provided at one end with an annular outwardly extending shoulder and with a head connected with said shoulder and substantially closing said barrel, said shoulder and head being integral with said barrel, and a hook member integral 30 with said head and comprising an arm connected with said head and extended laterally away therefrom, a flange extended from said arm at an angle thereto, and a

finger extended from said flange at an angle 40 thereto and toward said barrel substantially in the plane of said shoulder, substantially as described.

3. A one-piece sheet metal lacing hook of 45 the character described, comprising a barrel member provided at one end with an outwardly extended shoulder and with a head integral with said shoulder and said barrel and covering the latter, and a hook member comprising an arm integral with 50 said head and extended laterally therefrom beyond said barrel, a flange extended from said arm at an angle thereto and concaved transversely, and a finger extended from 55 said flange at an angle thereto and toward said barrel, said finger being concaved transversely, substantially as described.

4. A one-piece sheet metal lacing hook of 60 the character described, comprising a barrel member, a hook member integral with 65 and extended laterally from said barrel member and comprising an arm integral with the barrel and extended laterally away from said barrel member, a flange extended downwardly from said arm substantially at right angles thereto, and a finger extended from said flange substantially at right angles thereto and toward the side of said barrel member from which the said arm extends and substantially parallel with said 70 arm, substantially as described.

In testimony whereof, I have signed my name to this specification in the presence of two subscribing witnesses.

LESTER SLATER MACDONALD.
